Application September 20, 1945, Serial No. 617,578
In the Netherlands December 7, 1942

Section 1, Public Law 690, August 8, 1946
Patent expires December 7, 1962

7 Claims. (CL. 175—366)

1

In blocking-layer cells constituted by a carrier plate, a semi-conductive electrode, a blocking layer, a thin conductive electrode applied thereto (hereinafter briefly referred to as "blocking-layer cell of the selenium type"), in which a supply conductor is soldered to the latter, several drawbacks are encountered in regard of the properties of the conductive electrode at the point where the supply conductor is soldered to it.

These drawbacks particularly occur when the metal of the conductive layer easily alloys with the soldering metal. In fact, since the conductive layer is very thin, this layer will entirely dissolve in the soldering metal when it is applied to it so that at this place the specific properties of the cell, which are a function of the metal of the conductive electrode, may change completely in dependence of the soldering metal.

These drawbacks might be obviated by the use of a press-contact, but in this case there is again the danger that the conductive electrode might be pressed through and deteriorated, which leads to instability and even to short-circuiting of the cell.

These drawbacks chiefly occur with blocking-layer cells of small size, i. e. with those whose conductive electrodes have a surface smaller than 30 mm.², amongst others the so-called measuring cells, since with these measuring cells the metal of the conductive electrode has to satisfy particular requirements which serve to give a definite variation to the characteristic of the cell. In the case of larger cells, however, it generally suffices to reinforce the conductive layer at the place where the supply conductor must be secured. A material identical to that of the conductive layer may there be used for the soldering. Besides, in this case the soldered contact exhibits a small surface relatively to the surface of the whole cell, so that the influence upon the characteristic is small, if a change of the conductive electrode would occur, provided that this change does not impair the breakdown voltage.

Another difficulty involved with measuring cells is that the electrode is frequently so small that it is difficult to keep the soldering material solely within this surface. When it passes outside this surface, then in the first place the soldering metal will start to serve as an electrode, resulting in a variation of the characteristic curve, whilst in addition the capacity of the cell increases in a detrimental manner. The present

2

invention provides a construction in which these drawbacks are obviated.

According to the invention the conductive electrode is covered with an inert intermediate layer, on the other side of which lies the metal on which or in which the supply conductor is secured. The term "inert" has to be understood here to mean that the material does not disadvantageously react with or act upon the metal of the conductive electrode. The intermediate layer may consist, for example, of iron, aluminum or zinc. The metal of the conductive electrode may in this case consist of gold, bismuth, antimony or a bismuth-antimony alloy. The latter metals have been found to be particularly suitable for the manufacture of measuring cells. As a soldering material use may be made of the so-called alloy 103, consisting of tin, cadmium and bismuth.

According to another form of construction the intermediate layer may consist of a lacquer layer. As a lacquer ethyl-cellulose can very well be used. After hardening the lacquer layer is covered with a thin layer of metal, on which or in which the supply conductor is secured. As is well-known, in this case it is yet possible to obtain a conductive connection between the under-layer, hence the conductive electrode of the blocking-layer cell, and the metal layer.

The surface of the lacquer layer will generally not be limited to that of the conductive electrode, but rather be chosen of a larger size. Particularly in the case that the latter exhibits a very small surface, this saves much trouble. It has now been found with these cells that on applying the metal on which or in which the supply wire is secured, even when it occupies a larger surface than that of the conductive electrode, the capacity substantially does not increase. This may be accounted for by the fact that the lacquer layer has a thickness which is great relatively to the thickness of the blocking layer.

These steps are very appropriate to be applied to cells, the conductive electrode of which consists of gold and has a surface smaller than 30 mm.².

In order that the invention may be more clearly understood and readily carried into effect, it will be described more fully with reference to the accompanying drawing.

Figure 1 shows a blocking-layer cell in which a layer of inert metal is applied to the conductive electrode whereas

Figure 2 shows a blocking-layer cell in which

the cell is enveloped by a thin lacquer layer which has the supply conductor secured to it.

Both figures represent the cells on a greatly enlarged scale and only diagrammatically.

The blocking-layer cell shown in Figure 1 comprises a carrier plate 1 which has a selenium layer 2 applied to it. This selenium layer has formed on it a genetic or a non-genetic blocking layer 3 which has applied to it a conductive electrode 4 of gold having a small surface, for example of 1 mm. in diameter. This gold electrode has applied to it by vaporisation a thin layer of iron 5 which has secured to it a supply conductor 6 by means of a small quantity of solder 7. Since gold does not alloy with iron, the good properties of the gold electrode are thus ensured, but it is evident that in view of the small size of these parts there is a great danger that the iron or the soldering material 7 may pass outside the boundaries of the gold electrode. These drawbacks are largely suppressed by the construction shown in Figure 2. The blocking-layer cell shown in this figure comprises, as before, a carrier plate 1, a selenium layer 2, a blocking layer 3 and a conductive gold electrode 4. After the blocking-layer cell has been built up so far, it is dipped in lacquer, for which purpose ethyl cellulose is appropriate. The hardened lacquer layer, which is indicated by 8, has applied to it a thin layer 9 of alloy 103 in which a supply wire 6 is secured.

The thickness of the lacquer layer is estimated to be of the order of magnitude of 10 microns. It appears that in such a lacquer layer such apertures still exist that the metal layers on each side of the lacquer layer are in contact with one another. However, the lacquer layer prevents the conductive electrode from being dissolved, from forming an alloy or from being changed in any other way.

When use is made of the invention the thickness of the conductive electrode may be chosen much thinner—up to 10 times thinner—than it used to be.

The figure does not show the thickness of the various layers in the correct proportions. The blocking layer is much thinner than can be shown in the figure. It is evident that due to the small thickness of this blocking layer relatively to the thickness of the lacquer layer the capacity of the cell is fully determined by the surface of the elec-

trode 4 and not by that of the quantity of metal 9.

What I claim is:

1. A blocking-layer cell, comprising a carrier plate, a semi-conductive electrode, a blocking layer, a conductive electrode applied to said blocking layer, an intermediate layer of inert material deposited on at least a portion of the exposed surface of said conductive electrode, a metal contact layer applied to said intermediate layer, and a supply conductor secured to said metal contact layer.

2. A blocking-layer cell as claimed in claim 1, in which the intermediate layer consists of a metal which is chemically inert towards said conductive electrode.

3. A blocking-layer cell as claimed in claim 1, in which the intermediate layer consists of a lacquer layer.

4. A blocking-layer cell as claimed in claim 1, in which the intermediate layer consists of ethyl-cellulose.

5. A blocking-layer cell as claimed in claim 1, in which the intermediate layer covers a substantially greater surface than the surface area of the conductive electrode.

6. A blocking-layer cell as claimed in claim 1, in which the layer of metal to which the supply conductor is secured also covers a surface area which is larger than the surface area of the conductive electrode, and smaller than the surface area of the intermediate layer.

7. A blocking-layer cell as claimed in claim 1, in which the conductive electrode consists of gold and has a surface smaller than 30 mm.².
